SHIP FENDER

Zack B. Wasson, Dallas, Tex.

Application January 22, 1946, Serial No. 642,639

6 Claims. (Cl. 114—219)

1

This invention relates to a ship fender or bumper which has many advantages over the ordinary cane fender in that it can be disassembled and stored in a small space, is fireproof, can be readily replaced and colored as desired, as well as more efficiently absorbing the shock caused by ships bumping into each other or to a dock, when moored together or to a dock or wharf.

Another object of the invention is to provide a ship's fender which simulates a spider, and which involves spring elements designed to cushion the engagement of one ship against another or a dock or wharf in bumping into each other when moored together or to a dock, and which will efficiently absorb the shock thereof as well as permitting the same to be readily swung over the side of a ship by means of a line from the deck or otherwise.

Other objects and advantages reside in the details of construction and operation as more fully hereinafter described and claimed, reference being had to the accompanying drawings forming part hereof, wherein like numerals refer to like parts throughout, and in which:

Figure 1 is a front elevation of a ship's fender constructed in accordance with the invention.

Figure 2 is a side elevation thereof shown mounted for use between two ships when moored together.

Figure 3 is a sectional view taken on the line 3—3 of Figure 1.

Figure 4 is an inside elevation with parts omitted.

Figure 5 is an enlarged view in perspective of a top cover plate and cushioning anchor member, and

Figure 6 is a perspective view of a spring supporting plate.

Referring to the drawings in detail, in which reference characters designate corresponding parts throughout the several views, my ship or spider fender is shown as comprising a plurality of intersecting diametrical leaf springs 10, of curved formation, consisting of a top leaf 11, an intermediate leaf 12 longer than the top leaf 11 and a bottom leaf 13 which is longer than the leaf 12 intermediate of the leaves 11 and 13. These leaves are formed of flat spring material similar to a spring on an automobile or other

2

vehicle and of proper width and thickness to be determined according to the weight to be resisted and usually made of spring steel of proper temper and tension. The ends are disposed in stepped relation, and the extremities of the bottom leaf 13 are formed with curved or arcuate portions 14 having loops or eyes 15 inwardly of the extremities thereof on top. That is, these loops are disposed on the outside at the point where the spring leaves 13 are bent to form the curved ends 14. Intermediately, the several springs, such as three, cross one another in intersecting spaced divergent relation substantially 60° apart, although they may be otherwise related, thus forming a structure of substantially circular or hexagonal formation. Obviously, any number of springs may be employed intersecting each other as described and provided with intermediate apertures 16 by which the springs are mounted upon a common retaining shank or bolt 17 forming a central pivot member therefor. The bolt is mounted upon a top plate or cover 18 which may have a rubber or other cushion bumper 19 provided thereon and the opposite end 10 of the bolt, which is provided with a head plate 20 welded to plate 18, receives a telescopic spring support plate 21 which like the plates 18 and 20 is of circular formation. The plate 21 is provided with an offset frusto-conical depressed portion 22 and a plurality of spaced concentrically related openings 23 designed to receive threaded studs, shanks or bolts 24 anchored to and extending from the plate 18 to clamp the several sets of springs in position by means of nuts or other clamping devices 25 mounted on the ends of the bolts or studs 24. The depressed portion 22 of the plate 21 is provided with a central opening 26 to receive the threaded shank or bolt 17 which is held by a nut 27 and serves to mount a 20 tapered telescopic or conical coil spring 28 in position thereon seated at its small end in portion 22 centrally within the springs 10 to engage the side of a hull at its large end. The portions 14 form seats for the springs which are designed to 30 engage the side of a ship or hull in the manner shown in Figure 2 of the drawings, where two ships A and B are shown moored together, so that the present device serves as a fender to prevent the ships from bumping into each other and causing injury. The eyes or loops 15 may be welded

or otherwise secured in position and are designed to slidably receive a wire or cable 29, which is stretched between the various springs held in the relation specified if desired, between the bolts, studs or threaded shanks 24 in addition to being mounted centrally upon the bolt 17. Diametrically opposite sides of the fender are provided with spring connections 30 between certain end portions or intermediate portions of the cable or wire 29, being connected thereto at the ends of the springs and eyes 31 engaging apertured ears 32 of clamps 33 which are split and adapted to be clamped by means of bolts or screws 34 entering apertured ears 35 in the jaws of the clamps through which the wire or cable 29 extends in the manner shown in Figure 1 of the drawings so as to pass through openings at 36 in the inner sides of the clamp jaws adjacent to the eyes or ears 32. This leaves a portion or portions of the cable 29 loose between each pair of clamps 33 to permit springs 30 as indicated at 31, in order to take up slack or looseness therein, so as to maintain the cable taut in the normal position of the device and of the springs, but to allow expansion thereof upon pressure being exerted against the fender at the bumper 19 forming a cushion, when the ships strike against each other and the device is disposed against the side of the ship or hull, in the manner shown in Figure 2 of the drawings. The device may be suspended from three cables 38, which are fastened to loops 39 pivoted in straps or loops 40 secured to the inner faces of the spring leaves 13 by welding or otherwise, so that the loops 39 may pivot therein intermediate the arms of the springs from the bolts 17 and 24 outwardly thereof to the free ends of said spring leaves. In this manner, the device may be readily hung over the side of the ship for use and may be placed at the desired height by suitable means on deck. The spring 28 will therefore engage the hull and retain the device in position in conjunction with springs 10 and also resist compression under the bumping action between the ships. Thus, the springs 30 will serve to limit the slack between the portions of the cables which are connected to the spring leaves 13 of springs 10 near their extremities, and maintain the same taut, so that as the springs 30 are expanded or stretched, the slack will be paid out to limit the slack in the cable and take the strain as well as to stop the compression of the fender. It should also be noted that the cables 38 are attached to the upper ends of the leaves 13 of the springs 10 and the central cable attached to the highest or top leaf and the other two cables 38 attached at each side thereof to hold the fender in place fore and aft at the desired place and height in conjunction with the central cable which acts as a guide line so that the weight is supported at the top and placed at the center of gravity. Any number of such cables and loops or eyes 39 may be provided to hold the fender in place fore and aft. Also, suitable power means may be provided connected to the cables 38 in order to raise and lower the fender, such as a winch. Also, the cable 29 and springs 30 may be omitted if desired, especially where the ships are not large and heavy. The height of the fender from foot to top of the cushion, should be about 48 to 60 inches for a large ship but the size thereof will be determined by the size of the ship on which it is to be used, which will also determine the height or size and tension of the spring and leaves.

The device will have a great advantage over

the cane fender, as it can be readily disassembled and stored in a small place, is fireproof, can be readily replaced as to any part which may be in a state of disrepair, and may be painted and colored to agree with the color of the ship.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

What I claim is:

1. A ship's fender comprising a plurality of intersecting arcuate spring members, tensioning means connecting the end portions of said members, and means for intermediately connecting said members.

2. A ship's fender comprising a plurality of centrally intersecting spring members, means centrally connecting said members, said spring members being of arcuate formation, a cushioning spring projecting centrally at the concaved side of said members, and means for bracing said members in spaced divergent relation.

3. A ship's fender comprising a plurality of intersecting leaf spring members, and means for connecting said members intermediately in fixed divergent relation, said spring members being of arcuate formation, and extensible tension means movably connecting the ends of said spring members.

4. A ship's fender comprising a plurality of intersecting spring members, and means for connecting said members, said spring members being of arcuate formation and resilient means in the form of a cable and springs connecting the ends of said spring members.

5. A ship's fender comprising a plurality of intersecting leaf spring members, means for intermediately connecting said members, said spring members being of arcuate formation, clamping means between the members for holding said members in spaced divergent relation, said springs having leaves and curved seat portions at their ends, a central bumper at the convex side, a central cushioning member projecting from the concaved side, and means for suspending the fender over a ship's side in an upright position from certain of said spring members and for anchoring the same fore and aft.

6. A ship's fender comprising a plurality of arcuate spring members each comprising a plurality of leaf springs, means centrally connecting said springs in spaced divergent relation, inner and outer plates disposed centrally at the convex and concaved sides of the springs, connections between said plates extending between the springs to equidistantly space the same, a cushioning member on the plate at the convex side, a cushioning spring anchored to the connecting means at the concaved side and projecting therefrom to the plane of the ends of the springs, with reference to their extent of curvature at the concaved side, the extremities of the springs being curved to present the convex sides thereof toward a ship's hull, guides mounted on the concaved sides of said ends, a cable movably extending through said guides, springs interposed in said cable for taking up slack therein, loops

carried by adjacent portions of three springs and cables connected to said loops to suspend the device in upright position against the side of a hull from the central loop and to anchor the same fore and aft at the proper place and height at the side of the hull from the deck of the ship.

ZACK B. WASSON.
